[57] ABSTRACT

Electric discharge lamps having the fill of mercury and an inert-gas such as argon added with gallium and a halide such as iodine and bromine to make the light output rich in the vicinity of 400 mu wave length band to be adapted particularly for the light source for blue-printing, photolithography, in which gallium is added far excessive to the chemical equivalence for the gallium halide so that the gram-atom number ratio of gallium to the halide ranges from 0.5 to 3.0, whereby the satisfactory light output of the prior art type mercury lamp having the additive fill of gallium halide is kept and the disadvantage thereof, namely inevitably higher starting and reigniting voltages can be avoided.

FIG. 3

ELECTRIC DISCHARGE LAMPS

The invention relates to electric discharge lamps of mercury vapour added with usual inert-gas as well as gallium and a halogen such as iodine, bromine, and more particularly to an improvement of the lamps of such type to be made more suitable as the light source for photochemical reactions such as exposure of photo-sensitive agent for copier, photolithography and the like.

As well known, the photosensitive agents are particularly highly sensitive to the light of wave length band ranging from 380 to 420 m μ , although it may be varied more or less depending on the kind of the agents.

Hitherto the so-called mercury lamps, above all of high pressure mercury vapour type, have been used as the light source for those purposes. These mercury lamps, however, have their highest light output in the range of 365 m μ wave length so far as the band effective for photochemical reactions is concerned. Or in other words, a substantial portion of the radiation energy has been wasted. These conventional discharge lamps, thus, are not satisfactory in the efficiency of the exposure of the photosensitive papers and the like.

It has been already proposed in order to overcome these faults to add gallium iodide (GaI₃) to mercury and the inert-gas in the envelope, whereby the light output may be increased or strengthened in bands of 403 m μ and 417 m μ which correspond to the particular spectra of gallium. This recently developed lamp having an additional fill of gallium triiodide can radiate the light rich in the band approximately of 400 m μ so that it is surely satisfactory as the light source for exposing the copier sensitive papers and the like. It is still not satisfactory, however, in that relatively high voltages are necessary for starting and reigniting and that the voltages are apt to be raised as the lamp is used, although this is inevitable more or less in case of using an additive in the form of a metal halide. The cause has been acknowledged possibly due to impurities such as water and hydrogen inevitably mixedly introduced in the envelope together with the halogen or the metal halide as well as due to free halogen to be generated in the envelope. In order to avoid this disadvantage, it may be taken into consideration to decrease the amount of the halogen, above all iodine to be added, but it has been taken a strong hold of the persons skilled in the art that the halogen must be added in the amount of chemical equivalence relative to gallium. Even if the manufacturers take account of the possible weighing error, thus, the halogen has been added in the amount slightly less than the chemical equivalent.

We, the inventors, have exhausted various experiments to find unexpectedly against this technical common sense that it is possible to decrease the amount of the halogen such as iodine and bromine relative to gallium considerably from the chemical equivalent thereof whereby said fault can be completely avoided without lowering the light output in the wave length band of 380 m μ to 420 m μ .

The invention shall be explained in more detail in reference to the drawing, in which;

FIG. 1 is a diagram in which the light output of the mercury lamp having the fill of mercury vapour and argon added with gallium and iodine is shown in percentage in the ordinate relative to 100 percent in the wave length band of 380 m μ to 420 m μ of the light out-

put of the mercury lamp just same but involving no gallium nor iodine; and the gram-atom number ratio of gallium to iodine with varying the amount of the former relative to the fixed amount of the latter is taken in the abscissa;

FIG. 2 is a diagram in which the light output of the two mercury lamps having filling additives of gallium and iodine, one in the gram-atom ratio of 1:3 while the other of 1:1 with holding the gallium amount to be the same, is taken in the ordinate in percentage relative to 100 percent of the light output in the wave length band of 380 m μ to 420 m μ of the mercury lamp just same but without said additional fill; and the amount of gallium filled in the radiation envelope is shown in the abscissa variously changed in gram-atom per 1 cc. of the inner capacity of said envelope;

FIG. 3 is a cross-sectional view of a mercury discharge lamp embodying features of the invention.

In FIG. 3 a field envelope 10 is filled with mercury and an inert gas to which the components discussed have been added. A pair of electrodes 12 and 14 project through the envelope 10.

The inventors made experiments to obtain the results illustrated in FIG. 1 with using the 2 KW mercury lamp having a radiation envelope of 15 mm diameter and 200 mm effective length filled with 60 mg mercury and 15 mg argon as well as iodine in the amount of 0.98×10^{-6} gram-atom per 1 cc. of the inner capacity of said envelope to which gallium was added in a varied amount. In said figure, point A represents the light output in case where gallium was added relative to iodine in the gram-atom number ratio of 1:3 according to the prior art or the common sense in this technical field. It illustrates that said recently developed mercury lamp could improve the light output effective for the photochemical reaction two times in comparison with such an old mercury lamp as having the usual inert-gas but no additive referred to above. Points B, C and D respectively show the light outputs of the mercury lamps having gallium filled in the respective amounts relative to iodine in 1.5, 3.0 and 9.0 times the chemical equivalence to form gallium triiodide. As referred to above, it has been considered, although it goes without saying when the additional filling is introduced in the form of said compound, that gallium and iodine added respectively in the form of the element can contribute said improvement finally in the form of gallium triiodide in the envelope. If gallium should be useful merely in the form of said compound, addition or presence of such excessive amounts of gallium as 1.5, 3.0 and 9.0 times the chemical equivalent to iodine would at least not improve the light output characteristics or rather adversely affect thereon.

The results of our experiments showed, unexpectedly or against the conventional understanding, that such points B, C and D were all in far higher levels than point A. The mercury lamp having the additional fill consisting of gallium and iodine in the gram-atom number ratio of 1:2 showed the light output of 2.5 times the old mercury lamp, as shown by point B. The output was made 3 times in fact when said ratio was of 1:1, beyond expectation as shown by point C in FIG. 1. This unexpectedly wonderful result was still attained even if the amount of gallium was increased up to even 3 times the iodine content in the gram-atom number ratio, as shown by point D. The facts referred to above undoubtedly shows that gallium and iodine filled in the lamp en-

velope act on the photochemically effective light radiation at least not only in the form of gallium triiodide but also in combination of the lesser amount of iodine with gallium, although correct explanation on the phenomenon can not be made regrettfully at the present. There was acknowledged a very slight fall-down of the light output gradually toward said point D from point C possibly due to the excessive amount of gallium which will not react with iodine to be kept in the form of the element vapour which absorbs radiated light. The output was fairly sharply decreased when gallium was added in further excessive amount.

The amount of gallium to be filled in the envelope of the discharge lamp of this type generally and preferably ranges from 0.4×10^{-6} to 4.0×10^{-6} gram-atom per 1 cc. of the inner capacity of the envelope. Although said limits are not of course critical, when gallium to be added is less than said lower limit the spectrum of gallium is apt to be considerably decremented during the operation, while when it is more than said upper limit the discharge of the lamp is apt to be unstable. The inventors carried out the other type of experiments in which the light outputs were determined in respect of the mercury lamps as referred to above, one of which had gallium and iodine filled in the gram-atom number ratio of 1:3 as in the recently developed lamp and the other of 1:1. When the amount of gallium was varied to obtain the respective curves representing light output characteristics of said two discharge lamps, it was found that said characteristic curves were substantially coincident with each other as illustrated in FIG.

2. As readily appreciated therefrom, the discharge lamp having the additional filling of gallium and iodine in the ratio of 1:1 according to the present invention is not inferior at all to the lamp according to the prior art of which envelope was filled additionally with gallium and halide in the relative amount to form gallium triiodide.

Owing to the relatively lesser amount of iodine, the voltage necessary for starting the discharge lamp of the invention was about 700 V in comparison with 1,400 V of the lamp according to the prior art. The reigniting voltage was also made fairly lower. It was confirmed also that such voltages were not almost raised different from the lamp of the prior art having gallium and iodine filled in the ratio of 1:3.

The similar results were observed also in respect of the mercury lamp in which bromine was used in stead of iodine.

What is claimed is:

1. In electric discharge lamps having a sealed envelope which provides a pair of electrodes disposed therein and contains mercury and an inert-gas filled therein added with gallium and a halide selected from either of iodine and bromine, an improvement in that said gallium and said iodine are added in the gram-atom number ratio of from 0.5 to 3.0.

2. Discharge lamps as claimed in claim 1, in which said gallium is added in the amount of from 0.4×10^{-6} to 4.0×10^{-6} gram-atom per cubic centimeter of the envelope inner capacity.
